UNITED STATES PATENT OFFICE.

WALTER KOWALSKI, OF SPARTA, WISCONSIN.

STEAM CLOSET.

Application filed April 17, 1924. Serial No. 707,181.

To all whom it may concern:

Be it known that I, WALTER KOWALSKI, a citizen of Poland, residing at Sparta, in the county of Monroe and State of Wisconsin, have invented certain new and useful Improvements in Steam Closets, of which the following is a specification.

This invention relates to new and useful improvements in steam closets adapted for use for steam or vapor bath purposes.

An important object of the invention is to provide a closet or chamber within which a person may receive a steam bath.

A further object of the invention is to provide means for controlling the amount of steam admitted to the closet and the directness of application of the same to the body of the user.

A still further object of the invention is to provide improved means for delivering fresh air for breathing purposes to the occupant of the closet.

Other objects and advantages of the invention will be apparent during the course of the following description.

In the accompanying drawing forming a part of this specification and in which like numerals are employed to designate like parts throughout the same,

Figure 1 is a vertical sectional view of the steam closet embodying this invention,

Figure 2 is a top plan view of the steam closet shown in Fig. 1,

Figure 3 is a transverse horizontal sectional view taken upon line III—III of Fig. 1,

Figure 4 is a detail transverse sectional view taken upon line IV—IV of Fig. 3 and illustrates the seat or support for the user of the closet and the arrangement of a steam spray and valve structure associated therewith,

Figure 5 is a similar view to Fig. 4, but taken upon line V—V of Fig. 3,

Figure 6 is a detail elevational view of the fresh air supplying means associated with the steam closet illustrated in Figs. 1 and 3, and

Figures 7 is a detail transverse sectional view taken upon line VII—VII of Fig. 6.

In the drawing, wherein for the purpose of illustration is shown a preferred embodiment of this invention, the numeral 5 designates the cylindrical body portion of the closet which is substantially closed at its lower end by the dished bottom wall 6 and

is provided with a cone-shaped top wall 7 having diametrically arranged openings 8 formed therein. Depending from the dished bottom wall 6 are standards 9 which are connected to the base 10 that is provided with a plurality of casters 11 for permitting moving of the closet over the floor. The cylindrically-shaped body portion 5 is provided with a doorway 12 which is closed by the hinged door 13 having the latch mechanism 14 which may be operated either internally or externally of the closet by means of the handles 15.

Rotatably connected to the cone-shaped top wall 7 of the closet is a similarly-shaped valve 16 having diametrically arranged openings 17 which may be moved into and out of register with the openings 8 formed in the top wall 7 by means of the bar 18 which depends into the cylindrical body portion 5 of the closet. It will be understood that this valve structure permits ready communication with the outside atmosphere for enabling the closet to be quickly freed from live steam.

Positioned within the cylindrical body portion 5 of the closet is a seat 19 which is supported by the legs 20, as best illustrated in Figs. 1, 3, 4 and 5. This seat 19 is provided with a substantially rectangularly-shaped pocket 21 within which is slidably positioned the valve 22 having the handle portion 23. Connecting the pocket 21 with the top face of the seat 19 are a plurality of elongated slots 24 which are in vertical alignment with the elongated slots 25 that are formed in the seat 19 between the pocket 21 and the lower face of the former. It will be noted by inspecting Fig. 4 that these slots 25 have upwardly converging side walls, the purpose of which will be described at a later point.

Positioned below the seat 19 and in proximity thereto is a steam spray 26 which consists of a coil of pipe supplied with steam through the steam pipe 27 which is provided with a valve 28 for controlling the flow of steam therethrough. This coil is provided with a suitable series of apertures 29 through which the steam is discharged into the closet. This spray or coil 26 is provided with a discharge pipe 30 through which the steam that has not been discharged through the apertures 29 may be exhausted.

It will now be seen that the user of the closet may control the amount of steam be-

ing discharged into the closet by operating the valve 28 by means of the valve handle 28^a, also that the slide valve 22 may be operated for permitting the steam to be fed 5 upwardly through the slots 24 and 25 for directly applying the same to the body of the user or the valve may be closed for causing the steam to be entirely discharged into the closet without directly applying 10 the same to the user's body.

For the purpose of permitting the occupant of the closet to receive a supply of fresh air, a short section of pipe 31 is removably secured to the hinged door 13 by 15 means of the flange 32 carried by the pipe and the nut 33 which is threadedly connected to the end of the said pipe. Tele- 20 scopically mounted upon this pipe section 31 is a second pipe section 34 which is formed into an elongated bowl 35 at its free end which is provided with a rubber flange 36. The lower portion of this bowl-shaped portion 35 is provided with an operating knob 37 by means of which the user may slide 25 the bowl-shaped portion 35 into and out of operative engagement with his face.

For the purpose of handling the water of condensation which will naturally collect on the walls of the closet, a trough 38 is carried by the upper end of the cylindrically-shaped body portion 5 and is provided with a depending drain pipe 39 which carries the collected water of condensation to a point slightly above the dished bottom wall 6 where it is discharged thereon. A drain pipe 40 communicates with the lowest portion of the dished bottom wall 6 for the purpose of carrying off the water of condensation which collects thereupon.

It is now believed that the construction and operation of the steam closet embodying this invention will be understood by those skilled in the art. It might be well to note, however, that a person desiring to employ 45 the closet for obtaining a steam bath may enter the same through the doorway 12. The door 13 should then be closed and retained in this position by means of the latch 14. The rotary valve 16 should also be positioned for disalining the openings 8 and 17. After seating himself upon the seat 19, the slide valve 22 may be operated for regulating the degree of application of the steam to his body. The breather apparatus 50 should then be regulated and the steam admitted through the spray 26 by operating the valve handle 28^a. After the occupant

has remained in the steam filled closet the required length of time, the valve 16 may be operated for permitting the exhausting of 50 live steam from the closet. The valve 16 may be operated for permitting either a rapid or a gradual discharge of this steam and in this manner, the user's body may gradually be cooled or more rapidly cooled 55 as desired. The user may, of course, leave the closet through the opening 12.

It is to be understood that the form of this invention herewith shown and described is to be taken as the preferred example of 70 the same, and that various changes in the shape, size, and arrangement of parts may be resorted to without departing from the spirit of the invention or the scope of the 75 subjoined claims.

Having thus described the invention, I claim:—

1. In a cabinet of the class described, a seat having a series of slots therethrough, a perforated steam coil below said seat, a valve having a handle projecting laterally from beneath the seat to control the outflow of steam from said coil, and means for successively opening and closing said slots.

2. In a cabinet of the class described, a seat having a series of slots therethrough, a perforated steam coil below said seat, a valve having a handle projecting laterally from beneath the seat to control the outflow of steam from said coil, means for successively opening and closing said slots, a conical top on the cabinet having ports in its side, and valve means controlling the opening and closing of said ports and including a handle depending in front of a person 95 on said seat.

3. In a cabinet of the class described, a seat having a series of slots therethrough, a perforated steam coil below said seat, a valve having a handle projecting laterally from beneath the seat to control the outflow of steam from said coil, means for successively opening and closing said slots, a conical top on the cabinet having ports in its side, valve means controlling the opening 100 and closing of said ports and including a handle depending in front of a person on said seat, and a drip trough at the bottom of the top to prevent condensation dripping 105 on said seat.

In testimony whereof I affix my signature.

WALTER KOWALSKI.
